W.H. Parker
Steamboat Chimney.
N° 80659. Patented Aug. 4, 1868.

United States Patent Office.

W. H. PARKER, OF MEMPHIS, TENNESSEE.

Letters Patent No. 80,659, dated August 4, 1868.

IMPROVEMENT IN SMOKE-STACKS.

The Schedule referred to in these Letters Patent and making part of the same.

Be it known that I, W. H. PARKER, of Memphis, county of Shelby, and State of Tennessee, have invented a new and useful Improvement in Smoke-Stacks; and I do hereby declare that the following is a full, clear, and exact description of the construction and operation of the same, reference being had to the annexed drawings, making a part of this specification, in which—

Figure 1 is a perspective view.

Figure 2, a sectional view.

A A, boat.

E, F, and G, three sections of stack.

H, remnant of original stack.

B B, racks.

C C, latches.

D D, springs.

I I, spring-catches.

g, fulcrum.

A A A, levers.

I construct my boat in the usual form, to which I add an extra smoke-stack, constructed in three sections, on the telescope plan, which fits closely, when folded down, around the original chimney or smoke-stack.

The object of my invention is to provide men-of-war, and other steam-vessels, with an adjustable smoke-stack, constructed in such a manner that when the stack is in position it serves as a fire-jacket to the original stack, and, in case of the stack being injured by shot or accident, the adjustable stack can then be elevated to the position originally occupied by the other stack, as shown in fig. 2, where it is retained in position by means of the spring-catches I I.

My stack is elevated by operation of the levers A A A, which causes latches C C to act alternately upon racks B B, springs D D holding latches C C to racks B B.

I lower my stack by withdrawing the springs I I, by means of chains or ropes attached to the upper ends of said springs I I, and at the same time contracting and expanding, alternately, the lower or projecting ends of latches C C, in connection with the operation of levers A A A.

I claim the combination of three sections, E, F, and G, with the levers A A A, the latches C C, the springs D D, the racks B B, the three or more springs I I, the fulcrum g, constructed and operated substantially as herein set forth.
